UNITED STATES PATENT OFFICE.

HARRY AGLOW, OF NEW YORK, N. Y., ASSIGNOR TO THE NEW YORK LIGHTING FIXTURE MFG. CO., A CORPORATION OF NEW YORK.

DESIGN FOR A CHANDELIER.

Application filed December 23, 1926. Serial No. 20,120. Term of patent 3½ years.

To all whom it may concern:

Be it known that I, HARRY AGLOW, a subject of the King of Great Britain, and a resident of New York, county of Bronx, and State of New York, have invented a new, original, and ornamental Design for a Chandelier, of which the following is a specification, reference being had to the accompanying drawing, forming a part hereof.

The drawing shows a side view of the chandelier which is provided with arms for the support of candles or drop lights.

I claim:

The ornamental design for a chandelier substantially as shown and described.

HARRY AGLOW.
